LOUIS SCHNEIDER AND EDWARD E. J. DUQUETTE, OF ATLANTA, GEORGIA.

ROTARY-PLUG LOCK.

1,223,118.

Specification of Letters Patent. Patented Apr. 17, 1917.

Application filed May 26, 1916. Serial No. 100,137.

To all whom it may concern:

Be it known that we, LOUIS SCHNEIDER and EDWARD E. J. DUQUETTE, citizens of the United States, residing at Atlanta, in the 5 county of Fulton and State of Georgia, have invented certain new and useful Improvements in Rotary-Plug Locks; and we do hereby declare the following to be a full, clear, and exact description of the invention, 10 such as will enable others skilled in the art to which it appertains to make and use the same.

This invention may be said to relate to cocks and faucets, and more especially to 15 turning plugs; and when it is so used its object is to provide a lock for fastening the plug of a valve or bib after said plug has been turned to the desired position. The invention should not, however, be limited to 20 this specific use, as the lock may be applied to any turning member to hold it in any of a variety of positions to which it may be set; and it will be obvious without further illustration that it might be used to lock a plug 25 or similar member whose adjustment was longitudinal instead of rotary. The invention aims to provide a neat but serviceable lock of this character, actuated almost automatically by the user when he grasps the 30 handle of the plug, and almost or entirely concealed from view and therefore protected from dirt. A practical embodiment 35 of the idea is set forth in the following specification as applied to the turning plug of a hand valve for use on gas stoves, and reference is made to the accompanying drawings where—

Figure 1 is a vertical section through 40 most of the valve, showing the lock and its operating mechanism in full, Fig. 2 is an enlarged detail of the locking bolt and the rock lever for sliding it, Fig. 3 is a horizontal section on the line 3—3 of Fig. 1, and Fig. 4 is a similar sectional detail showing a 45 slight modification.

Broadly speaking, this invention provides means for locking a male member M which is rotatable within a female member F, but as shown in the drawings these members 50 constitute respectively the plug and the casing of a bib or valve, whose openings are indicated in dotted lines at m and f. S is the stem of the plug, and H is its handle. As suggested above, the invention is not confined to this use nor the parts to the shape 55

shown, and it is quite obvious that they could be made in a variety of shapes.

Coming now to the details of the present invention, the numeral 1 designates a bolt 60 slidably mounted in a guide 2 which is herein shown as a hole passing transversely through the stem S, or part way through it as indicated in Fig. 4.

The female member F is herein shown as a valve casing having an upstanding collar 65 3 provided at one side with a cut-out or channel 4 extending through an arc of 90 degrees, and internally bored with sockets 5 and 6 respectively opposite the extremities of said channel so as to receive the tip of the 70 bolt 1, while the other end of the bolt travels in the channel and limits the turning of the member M. In the modification shown in Fig. 4 the guide is not so long and the bolt does not extend completely through the 75 plug, and therefore no channel 4 is necessary; and it is quite obvious that a number of sockets or notches 7 could be provided for the tip of the bolt, and the latter could be reduced or pointed as shown. When the 80 invention is applied to a bib or faucet and the ports m and f stand in alinement as seen in dotted lines in Fig. 1, the bib is open and the tip of the bolt stands in the socket 6. When now the bolt is retracted so that its 85 tip is disengaged from said socket, the plug can be turned for a quarter revolution while the other end of the bolt travels in the channel 4, and then after the bib is closed the tip of the bolt can be projected into the 90 socket 5 to lock the bib in that position.

The mechanism for moving the bolt is designed to be concealed from view and protected from dust and dirt. To this end the stem S of the plug M is made hollow and 95 in its bore 10 is mounted a rock lever 11 pivoted between its ends as at 12, its tip engaging a notch or other opening in the bolt 1 as best seen in Fig. 2. Pivotedly connected at 13 to its other end here its upper 100 end is a link 14 moving freely within an opening 15 extending from the bore 10 laterally to one side of the stem at its upper end, the link having its outer end provided with a hook 16. The handle H is also made hollow, and its bore 20 is enlarged at its outer end into a cavity 21 so as to produce a shoulder 22, the inner end of the handle 105 preferably carrying a ferrule 23. A screw 24 passes through said bore and engages the 110

head of the stem, and an expansive spring 25 is coiled on this screw within the cavity 21 between the shoulder 22 and a washer 27 which underlies the head of the screw. 5 Finally the ferrule is provided with an eye as indicated at 26, into which the link 14 extends so that its hook 16 is engaged with the eye.

The parts being assembled as best seen in 10 Fig. 1, when it is desired to turn the plug the operator grasps the handle H and moves it slightly to the right as the compression of the spring 25 will permit. This moves the ferrule 23 away from the head of the 15 stem, and through the hook 16 the link is caused to move with it and the rock lever 11 is caused to swing to the position shown in dotted lines in Fig. 2. The tip of this lever engaging the notch 12 in the bolt, retracts 20 the latter so that it disengages the socket 6, and then when the operator swings the handle H to turn the stem S and member M, the opposite end of the bolt moves in the channel 4 until the valve plug has turned 25 through a quarter rotation when the operator releases the handle the spring restores the parts to their normal position and the tip of the plug enters the notch 5. It is obvious that the same operation would take 30 place if the bolt were shorter and the channel 4 omitted as seen in Fig. 4, and it is also obvious that the plug could be adjusted to a number of positions if the sockets were quite plentiful as indicated at 7 in this view. 35 It will also be obvious that the invention could be applied to turning members other than valve plugs, and also possibly to members whose movement was not rotary, as, for instance, to members which moved longitudinally. The gist of the invention lies 40 in the fact that when the operator grasps the handle to set the member M, he can almost without conscious effort move the handle a little to retract the bolt 1 and unlock 45 such member before he sets it; and provision is made for the automatic locking of the bolt when he releases the handle.

For the purpose of preventing a slight rotation of the handle which might draw on 50 the link undesirably, it may be provided at its inner end with a pin 30 which slides in and out of a hole 31 in the stem S of the plug. We do not wish to be limited to this detail, however, as any means may be provided for effecting this end.

What is claimed as new is:

1. The combination with a female member having a series of sockets, a male member movably mounted in the female member 60 and having a guide in the line of said series, and a bolt slidably mounted in the guide and adapted to be projected into any of said sockets according to the relative position of the members; of a handle movably attached 65 to the male member for adjusting its posi-

tion in the female member, and connections between the handle and bolt whereby the movement of the handle with respect to the male member actuates the bolt.

2. The combination with a casing having 70 an upstanding collar containing a series of sockets, and a plug movably mounted in said casing and having a guide in the plane of said sockets; of a bolt movably mounted in the guide, a rock lever pivoted to the stem 75 of the plug and having one end engaging the bolt, a handle movably mounted on the head of said stem, and connections between the handle and the other end of the lever.

3. A turning plug and a casing, the former having a hollow stem provided with a guide intersecting its bore, and the casing having a plurality of sockets in the plane of said guide; combined with a bolt slidably mounted in said guide, a rock lever disposed 80 within said bore and pivoted between its ends and its lower end engaging said bolt, the outer end of said stem having a lateral opening communicating with its bore, a pin 85 projecting laterally from this end of the stem, a handle slidably mounted on said pin, and a link pivoted to the outer end of the rock lever, extending through said bore, and engaging the handle.

4. A casing, and a rotary hollow member 95 therein provided with a guide intersecting its bore, the casing having a plurality of sockets in the plane of said guide; combined with a bolt slidably mounted in said guide, a rock lever disposed within said bore and pivoted between its ends with its lower end 100 engaging said bolt, the outer end of said member having a lateral opening communicating with its bore, a pin projecting laterally from this end of the member, a handle 105 slidably mounted on said pin, a ferrule surrounding the inner end of the handle and having an eye, and a link pivoted to the outer end of the rock lever, extending through said lateral opening, and having a 110 hook engaging the eye in the ferrule.

5. A valve comprising a turning plug and a casing, the former having a hollow stem provided with a guide intersecting its bore, and the casing having a plurality of sockets 115 in the plane of said guide; combined with a bolt slidably mounted in said guide, a rock lever in said bore with its lower end engaging said bolt, the outer end of said stem having a lateral opening communicating with its 120 bore, a screw projecting laterally from this end and having an expansive spring beneath its head, a hollow handle slidably mounted on said screw and having a cavity inclosing the spring and against whose inner end said 125 spring bears, and a link pivoted to the outer end of the rock lever, extending through the opening, and engaging the handle.

6. A valve comprising a turning plug and a casing, the former having a hollow stem 130

- provided with a guide, and the casing having an arcuate channel in one side and opposite thereto a plurality of sockets in the plane of said guide; combined with a bolt slidably 5 mounted in said guide, a rock lever disposed within said bore and with its lower end engaging said bolt, the outer end of said stem having a lateral opening communicating with its bore, a pin projecting laterally from 10 this end of the stem, a handle slidably mounted on said pin, a ferrule surrounding the inner end of the handle and having an eye, and a link pivoted to the outer end of the rock lever, extending through the opening, and having a hook engaging the eye in 15 the ferrule.
7. A valve comprising a turning plug and a casing, the former having a hollow stem provided with a transverse guide intersecting its bore, and the casing having a plurality of sockets in the plane of said guide; combined with a bolt slidably mounted in 20 said guide and having a notch alined with the bore, a rock lever disposed within said bore and pivoted between its ends, its lower end engaging the notch in said bolt, the outer end of said stem having a lateral opening communicating with its bore, a screw projecting laterally from this end and 25 having an expansive spring beneath its head, a hollow handle slidably mounted on said screw and having a cavity inclosing the spring and against whose inner end said spring bears, a ferrule surrounding the 30 inner end of the handle and having an eye, and a link pivoted to the outer end of the rock lever, extending through the opening, and having a hook engaging the eye in the ferrule.
8. A valve comprising a turning plug and a casing, the former having a hollow stem provided with a transverse guide intersecting its bore, and the casing having an arcuate channel in one side and opposite thereto a plurality of sockets in the plane of said guide; combined with a bolt slidably mounted in said guide and having a notch alined with the bore, a rock lever disposed 35 within said bore and pivoted between its ends, its lower end engaging the notch in said bolt, the outer end of said stem having a lateral opening communicating with its bore, a screw projecting laterally from this end and having an expansive spring beneath its head, a hollow handle slidably mounted on said screw and having a cavity inclosing the spring and against whose inner end said spring bears, a ferrule surrounding the 40 inner end of the handle and having an eye, and a link pivoted to the outer end of the rock lever, extending through the opening, and having a hook engaging the eye in the ferrule.
9. A valve comprising a turning plug and a casing, the former having a hollow stem provided with a transverse guide intersecting its bore, and the casing having a plurality of sockets in the plane of said guide; combined with a bolt slidably mounted in said guide and having a notch alined with the bore, a rock lever disposed 45 within said bore and pivoted between its ends, its lower end engaging the notch in said bolt, the outer end of said stem having a lateral opening communicating with its bore, a screw projecting laterally from this end and having an expansive spring beneath its head, a hollow handle slidably mounted on said screw and having a cavity inclosing the spring and against whose inner end said spring bears, a ferrule surrounding the 50 inner end of the handle and having an eye, and a link pivoted to the outer end of the rock lever, extending through the opening, and having a hook engaging the eye in the ferrule.
10. A valve comprising a turning plug and a casing, the former having a hollow stem provided with a transverse guide intersecting its bore, and the casing having a plurality of sockets in the plane of said guide; combined with a bolt slidably mounted in said guide and having a notch alined with the bore, a rock lever disposed 55 within said bore and pivoted between its ends, its lower end engaging the notch in said bolt, the outer end of said stem having a lateral opening communicating with its bore, a screw projecting laterally from this end and having an expansive spring beneath its head, a hollow handle slidably mounted on said screw and having a cavity inclosing the spring and against whose inner end said spring bears, a ferrule surrounding the 60 inner end of the handle and having an eye, and a link pivoted to the outer end of the rock lever, extending through the opening, and having a hook engaging the eye in the ferrule.

In testimony whereof we affix our signatures in presence of two witnesses.

LOUIS SCHNEIDER.

EDWARD E. J. DUQUETTE.
